RIVETING MACHINE

Clyde Thiele, Hampton, Va.

Application July 26, 1941, Serial No. 404,115

4 Claims. (Cl. 78—48)

(Granted under the act of March 3, 1883, as amended April 30, 1928; 370 O. G. 757)

This invention relates to riveting machines and it has a particular relation to machines of the portable type employed in riveting together relatively thin sheets and plates.

The principal object of the present invention is the provision of a riveting machine of the type described having an anvil of simple and rugged construction slidably mounted on the hammer for backing up a rivet during the upsetting operation and which may quickly and easily be removed for replacement by another anvil of different size according to the nature and size of the work.

With these and other objects in view, as well as other advantages that may be incident to the use of the improvements, the invention consists in the parts and combinations thereof hereinafter set forth and claimed, with the understanding that several necessary elements constituting the same may be varied in proportion and arrangement without departing from the nature and scope of the invention, as defined in the appended claims.

In order to make the invention more clearly understood, there are shown in the accompanying drawing, means for carrying the invention into practical use, without limiting the improvements in their useful application to the particular construction, which, for the purpose of explanation have been made the subject of illustration.

The single figure of the accompanying drawing is a view partly in side elevation and partly in longitudinal section of a riveting machine constructed in accordance with the invention.

Referring to the drawing the improved riveting machine is shown as comprising a riveting gun 10 of any suitable commercial type and operated either electrically or pneumatically. A hammer 11 in the form of an elongated rod is resiliently secured to the forward end of the gun 10 by means of a tightly wound coiled spring 12, engageable with a head 13 formed on the hammer 11. The forward end of the hammer 11 is provided with a removable riveting tip 14 of suitable size and configuration for engagement with a rivet 15 securing plates 16 together.

During the riveting operation the rivet 15 is backed up by a yoke 17 having a leg 18 overhanging the end of the hammer 11 and forming an anvil engageable by the rivet and a leg 19 terminating in a longitudinally extending portion 20 provided with a pair of spaced lugs 21 and 22 for slidably engagement with the hammer 11. The yoke 17 is urged rearwardly and the anvil 18 toward the riveting tip 14 by a coiled spring 55

23 which encircles the hammer 11 between the lugs 21 and 22. This spring abuts the lug 22 and a washer 24 which is removably held in position on the hammer by a spring clip 25 engageable with a circumferential groove 26 formed in the hammer.

A sleeve 27 is also slidably mounted on the hammer 11 between the rear end of the portion 20 of the yoke 17 and the hammer attaching spring 12 and is yieldably maintained in abutting engagement with the former by a coiled spring 28 which is interposed between a collar 29 formed on the sleeve and a washer 30 mounted on the hammer 11 and abutting the spring 12. The sleeve 27 is formed with a pair of upwardly extending spaced ears 31 between which a lever 32 is pivotally mounted. The lower end of this lever is formed with a cam 33 which is held by the spring 28 in engagement with a slot 34 provided in the rear end of the portion 20 of the yoke.

It will be noted from an inspection of the drawing, that when the lever 32 occupies the upright position illustrated in full lines, the spring 23 is free to slide the yoke 17 rearwardly on the hammer so as to clamp the rivet 15 between the tip 14 of the hammer and the anvil during the upsetting operation. When, however, the riveting operation is completed the lever 32 is swung rearwardly and downwardly to the position shown by broken lines in the drawing in which position the cam 33 forces the yoke 17 bodily to the position illustrated by the broken lines and against the action of the spring 23 so as to release the work.

When it is desired to substitute a yoke of another size so as to accommodate work of different size, it is only necessary to release the spring clip 25 which will permit the entire assembly to be slid off of the hammer.

It will be understood that the above description and accompanying drawing comprehend only the general and preferred embodiment of the invention and that various changes in construction, proportion and arrangement of the parts may be made within the scope of the appended claims without sacrificing any of the advantages of the invention.

The invention described herein may be manufactured and used by and for the Government of the United States of America for governmental purposes without the payment of any royalties thereon or therefor.

I claim:

1. A riveting machine comprising a riveting

gun, an elongated hammer mounted thereon for transmitting impacts delivered thereto by said gun longitudinally thereof to a rivet, a removable anvil slidably mounted on said hammer, resilient means for urging said anvil toward said hammer to grip a rivet to be riveted therebetween and manually operable means mounted on said hammer for engagement with said anvil to move the same away from said hammer against the action of said resilient means to release the rivet.

2. A riveting machine comprising a riveting gun, an elongated hammer mounted thereon for transmitting impacts delivered thereto by said gun longitudinally thereof to a rivet, a yoke having one leg slidably mounted on said hammer and the other leg overhanging the end of said hammer and forming an anvil therefor, abutments on said hammer and said yoke, a spring encircling said hammer between said abutments for urging said anvil toward said hammer to grip a rivet to be riveted therebetween and manually operable means mounted on said hammer for engagement with said anvil to move the same away from said hammer against the action of said resilient means to release the rivet.

3. A riveting machine comprising a riveting gun, an elongated hammer mounted thereon for transmitting impacts delivered thereto by said

gun longitudinally thereof to a rivet, a removable anvil slidably mounted on said hammer, resilient means for urging said anvil toward said hammer to grip a rivet to be riveted therebetween and manually operable cam mounted on

5 said hammer for engagement with said anvil to move the same away from said hammer against the action of said resilient means to release the rivet.

10 4. A riveting machine comprising a riveting gun, an elongated hammer mounted thereon for transmitting impacts delivered thereto by said gun longitudinally thereof to a rivet, a yoke having one leg slidably mounted on said hammer and the other leg overhanging the end of said hammer and forming an anvil therefor, abutments on said hammer and said yoke, a spring encircling said hammer between said abutments for urging said anvil toward said 15 hammer to grip a rivet to be riveted therebetween, a manually operable cam mounted on said hammer for engagement with said anvil to move the same away from said hammer against the action of said resilient means to release the rivet, and a spring encircling said hammer for 20 urging said cam into engagement with said yoke.

25 CLYDE THIELE.
